UNITED STATES PATENT OFFICE.

WILLIAM J. PARSONS, OF MILLERS FALLS, MASSACHUSETTS, ASSIGNOR TO MILLERS FALLS COMPANY, OF MILLERS FALLS, MASSACHUSETTS, A CORPORATION OF MASSACHUSETTS.

DESIGN FOR AN AUTOMOBILE-TIRE WRENCH.

49,037.

Specification for Design.

Patented May 9, 1916.

Application filed January 30, 1915. Serial No. 5,318. Term of patent 3½ years.

To all whom it may concern:

Be it known that I, WILLIAM J. PARSONS, a citizen of the United States, and resident of Millers Falls, town of Montague, in the county of Franklin and State of Massachusetts, have invented a new, original, and ornamental Design for an Automobile-Tire Wrench, of which the following is a specification, reference being had to the accompanying drawing, forming part thereof, of which—

Figure 1 shows a side view, and Fig. 2 an edge view.

I claim:

The ornamental design for an automobile tire wrench as shown.

WILLIAM J. PARSONS
